UNITED STATES PATENT OFFICE

WALTER G. HEGINBOTTOM AND JACOB RICHARD FRANCIS, OF FLINT, MICHIGAN; THE UNION INDUSTRIAL TRUST COMPANY AND ANNA HEGINBOTTOM EXECUTORS OF SAID WALTER G. HEGINBOTTOM, DECEASED

CARBURETOR

Application filed January 23, 1924. Serial No. 688,052.

This invention relates to carburetors, the object being to provide an air valve which is interconnected with the throttle of the carburetor for the purpose of varying the vacuum in the mixing chamber at various throttle positions.

Another object of the invention is to provide means for varying the tension of the spring controlling the air valve in the form of a cam carried by the throttle valve stem and so constructed that the tension of the spring is automatically increased when the throttle valve of the carburetor is in substantially closed position or substantially full open position, whereby the mixture will be heavier when the internal combustion engine is idling or running at high speed.

Another and further object of the invention is to provide a construction of carburetor and loading valve which can be manufactured cheaply, the parts being so arranged and interconnected that all danger of these parts getting out of order when in operation are prevented, additional means being provided for setting the air valve so as to obtain the proper proportion of gas and air prior to the actuation of the means for adjusting the tension of the air valve.

Other and further objects and advantages of the invention will be hereinafter set forth and the novel features thereof defined by the appended claims.

In the drawings,

Figure 1 is a side elevation of a carburetor, partly in section, showing the application of our improved construction of means for varying the tension of the air valve spring;

Figure 2 is a detail side elevation, partly in section, showing the throttle valve partially open; and

Figure 3 is a similar view showing the throttle valve in full open position.

In the embodiment of the invention as herein shown 1 indicates the body of a carburetor which is provided with a fuel bowl 2 and a fuel nozzle 3 extending into the mixing chamber 4, which is provided with an outlet 5 having a flange 6 of the usual construction connecting the same to the intake manifold of an internal combustion engine. The body is

provided with an air inlet 7 controlled by an air valve 8 provided with a threaded stem 9 on which is mounted an adjusting sleeve 10 in the opposite end of which is secured a bolt 11.

The flange 6 is provided with an extension 12 provided with a stud 13 on which is mounted a bell crank 14, the arm 15 of which is provided with a ball 16 for the purpose hereinafter fully described. The arm 17 of the bell crank 14 is provided with a bifurcated bearing, in the furcation of which is mounted the eye of a bolt 11 on a pin 19, whereby as the bell crank 14 is rocked, the position of the air valve 8 will be adjusted in respect to its seat.

The stem 9, sleeve 10 and bolt 11 form an adjustable connection between the bell crank and the valve for adjusting the position of the valve in order to get the proper proportion of gas and air.

Mounted within the upper end of the mixing chamber is a throttle valve 20 carried by a stem 21 extending transversely through the walls of the mixing chamber and provided with a cam 22 which is provided with a lip 23 and a lobe 24 for the purpose hereinafter fully described.

Arranged on the side of the body of the carburetor is a tubular casing 25 provided with a bearing mounted on the throttle shaft at its inner end and supported at its outer end by the ball 16 of the arm 15 of the bell crank 14 which is movably mounted in the casing, said casing being provided with a slot 26 through which the arm passes as clearly shown in Figure 1.

Disposed within the casing 25 is a coil spring 27 which engages the ball 16 at one end and a ball 28 at its opposite end, which is loosely mounted within the casing. This end of the casing is contracted and slotted as shown at 29 to receive the cam 22 and when the throttle is in substantially closed position, the lip 23 of the cam is in contact with the ball 28 so as to increase the tension of the spring in order to resist the opening of the air valve 8 so as to increase the vacuum within the mixing chamber of the carburetor.

The valve stem 21 is provided with the

usual operating lever 30 and is adapted to be connected to the controlled means in the usual manner and as the throttle valve is moved into position as shown in Figure 2, the tension 5 of the spring is reduced so as to weaken the mixture at intermediate speeds. As the throttle valve is moved into full open position, the lobe 24 of the cam forces the ball inwardly so as to increase the tension of the 10 spring which has a tendency to resist the opening of the air valve to increase the richness of the mixture.

It will be seen that when the throttle valve is in substantially closed position and in full 15 open position, we obtain greater depression in the mixing chamber, thereby feeding the heavier mixture of gas to the internal combustion engine at idling speed and full speed.

In order to provide a carburetor with an 20 economical range, say from 10 miles an hour to 50 miles an hour, it is essential to provide means for supplying a rich mixture to the internal combustion engine at idling speed and full speed and a lean mixture at intermediate speed, and by the particular construction of automatic control of the tension of the spring by the movement of the throttle, we are able to accomplish this result.

By having an independent adjustment for 30 the air valve, we are able to adjust the same independent of the movement of the throttle so as to set the instrument and while we have shown certain details of construction of air valve and means for adjusting the same, we 35 are aware that various changes can be made without departing from the spirit of our invention, which consists broadly in providing means for adjusting the tension of the air valve spring at different throttle positions.

40 What we claim is:—

1. A carburetor for internal combustion engines comprising a body provided with a mixing chamber and a valve controlled air inlet, a bell crank mounted on said body, an 45 adjustable connection between one arm of said bell crank and said air valve, a spring bearing against the other arm of said bell crank, a throttle valve mounted in said body and a cam carried by said throttle valve for 50 increasing the compression of said spring at high and low speeds and for decreasing the compression of said spring at intermediate speed.

2. A carburetor comprising a body provided with a mixing chamber having a throttle valve for controlling the outlet and an air valve for controlling an air inlet therefor, a bell crank mounted on said body having a connection with said air valve, a casing 55 mounted on the throttle shaft having a spring mounted therein engaging one of the arms of said bell crank, a ball arranged at the other end of said spring within said casing and a cam mounted on the throttle valve having a 60 lip and a lobe for increasing the compression

of said spring at high and low speeds and for decreasing the compression of said spring at intermediate speed.

3. A carburetor comprising a body provided with a mixing chamber having a throttle valve controlling the outlet, said body being provided with a valve controlled air inlet, a bell crank mounted on said body and an adjustable connection between said bell crank and said air valve, a casing carried by the 70 throttle shaft in which one end of said bell crank is disposed, a spring arranged in said casing adjacent said bell crank, a ball arranged in said casing engaging the other end of said spring and a cam mounted on the 75 throttle valve engaging said ball and so constructed that the compression of said spring is increased at high and low speeds and reduced at intermediate speed for varying the vacuum within said mixing chamber.

4. A carburetor for internal combustion engines having a mixing chamber provided with a throttle valve controlling the outlet thereof and an air inlet and air valve therefor, a spring disposed within a casing for normally holding said air valve in a predetermined position, a ball disposed in said casing engaging said spring and a cam carried by the throttle valve for increasing the compression of said spring at high and low 90 speeds and reducing the compression of said spring at intermediate speeds for varying the vacuum within said mixing chamber.

In testimony whereof we hereunto affix our signatures.

WALTER G. HEGINBOTTOM.
JACOB RICHARD FRANCIS.
